TARGET

Fred W. Schaffner, Mount Washington, Ohio

Application January 23, 1943, Serial No. 473,297

6 Claims. (Cl. 273—102)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to targets and more particularly to a target adapted for testing the accuracy of rifles on a testing range.

An object of this invention is to provide a target for small arms and the like adapted for easy sighting, particularly at fixed range.

A further object of this invention is to provide a target having a conventional target pattern and having superimposed thereon a sighting bull's-eye of a size which is related to the range at which the target will be used.

A further object of this invention is to provide a testing target permitting rapid, accurate testing of small arms and the like in mass production.

Another object of this invention is to provide a relatively simple and economical testing target for rifles.

Another object of this invention is to provide a testing target which minimizes the personal factor involved in testing small arms.

Another object of this invention is to provide a target for small arms and the like suitable for instruction of persons in target shooting.

Still further objects and advantages of the invention will be in part apparent and in part pointed out in the following description of a preferred embodiment as shown in the accompanying drawing, in which:

Fig. 1 is a view of a conventional target.

Fig. 2 is a view of a target according to the invention.

Fig. 3 is a view of the sighting alignment of a small firearm using the conventional target of Fig. 1.

Fig. 4 is a view of the sighting alignment of a small firearm using a target according to the invention.

Figs. 5, 6 and 7, are views of modified targets within the purview of the invention.

In sighting a rifle having a front blade sight and a rear peep sight, the top of the blade is centered in the aperture of the rear sight and, holding this alignment, the top of the blade sight is positioned so that the bottom of the bull's-eye of the target appears to be tangent to the top of the blade and the center of the bull's-eye is in alignment with the vertical axis of the front blade. This is the correct alignment of the sights and target irrespective of the range, and is illustrated in Fig. 3 of the drawing, wherein 1 rep-

2

resents the rear peep sight, 2 represents the front blade sight and 3 represents the bull's-eye of the conventional target shown in Fig. 1.

Referring for a moment to Fig. 1, the target proper is shown at 4. Surrounding the bull's-eye 3 are a number of concentric rings 5 providing various scoring zones of value diminishing outwardly from the center.

It will be seen that the apparent relative sizes 10 of the front sight 2 and rear sight 1 are approximately fixed for any one marksman, but that the apparent size of the bull's-eye 3 is dependent upon the range. It will be further understood that there is one particular range at which the 15 diameter of the bull's-eye 3 will appear to be equal to the apparent width of the front blade sight. It has been found that at this particular range, sighting is greatly simplified because of the ease with which the vertical sides of the 20 front sight are aligned with the edges of the bull's-eye. For all other ranges, the apparent size of the bull's-eye will not allow of such easy sighting.

Rifles produced in large volume must be 25 proofed, and a proofing procedure has been adopted involving the use of a standard target having a fixed size of bull's-eye and used at a fixed range. Under these conditions the bull's-eye 3 is too small completely to fill out the width 30 of the front sight. While vertical aiming of the gun is relatively simple, lateral aiming is much more difficult because it involves the alignment of the estimated center of the bull's-eye with the estimated vertical axis of the front sight. The 35 personal equation, therefore, plays a major role in causing lateral dispersion of shot groups of different riflemen.

I have overcome the above mentioned sighting difficulties by superimposing upon the conventional target a sighting bull's-eye 7 (Fig. 2), of a size differing from the conventional scoring bull's-eye 8, corresponding to 3 of Fig. 1. The sighting bull's-eye differs in size from the scoring bull's-eye, the size of the former being selected 45 for the particular range and apparent relative dimensions of the front and rear sights of the rifle, and the size of the latter being selected in relation to the ballistic characteristics of the rifle. The sighting bull's-eye is designed in the 50 figures shown to just fill the space between the vertically extended sides of the front sight. Of course, the sighting bull's-eye may be smaller or larger than the scoring bull, again depending upon the range.

For every target there is selected an arbitrary

aiming point. Conventionally, in a target having a circular bull's-eye, this aiming point is designated as the lowest point of the bull's-eye, commonly referred to as the "6 o'clock" position. I have so located my super-imposed sighting bull's-eye that its aiming point coincides with the aiming point of the scoring bull's-eye, and the vertical diameters of the two bull's-eyes also coincide insofar as their respective lengths permit. This is clearly shown in Fig. 2 wherein the sighting bull's-eye 7 and the scoring bull's-eye 8 are tangent at their lowest points. Such an arrangement makes it immaterial which of the two bull's-eyes is used for sighting and the aiming of the gun is thus not affected. However, the large bull's-eye makes it easier properly to align the rifle with the target.

An inspection of Fig. 4 will show the correct alignment of the rifle with the target using the improved sighting bull's-eye.

Alternative modifications of my improved target are shown in Figs. 5, 6 and 7, wherein the target is shown aligned with the sights of a rifle. In Fig. 5, 9 is the scoring bull's-eye and 10 is the sighting bull's-eye which latter is semi-circular in shape. In Fig. 6, 11 is the scoring bull's-eye and 12 is a square sighting bull's-eye. A similar device is shown in Fig. 7 in which 13 is the scoring bull's-eye and 14 is a triangular sighting bull's-eye.

The material of construction of the target forms no part of the present invention. It may be made in any convenient manner, as will readily be apparent to one skilled in the art. A printed target is to be preferred, but a target may conveniently be made by superimposing a cut-out bull's-eye in proper relation upon a conventional target.

It will be apparent that many modifications within the scope of the invention may be constructed by one skilled in the art in the light of the disclosure of this specification.

The modifications shown and described herein are to be taken as merely illustrative of the invention, and not limitative thereof, the following claims defining the scope of the invention.

I claim:

1. A target comprising a circular scoring bull's-eye and a circular sighting indicium eccentric to and larger in size than said bull's-eye, the periphery of said bull's-eye being internally tangent to the periphery of said sighting indicium at the lowermost point thereof.
2. A target for a gun equipped with a rear sight having a peep-hole and a front sight having an upstanding blade, said target comprising a first bull's-eye and a series of rings concentric thereto and demarking zones of radially outwardly di-

minishing score values, there being a second bull's-eye superimposed over and larger than said first bull's-eye, said first and second bull's-eyes having one point only of the lowermost portions of their peripheries in common, and said second bull's-eye having a transverse dimension equal to that subtended by said blade when viewed through said peep-hole from a predetermined range.

3. A target for a gun equipped with a front sight having an upstanding blade and a rear sight having a peep-hole through which said blade and the target are viewed in sighting, said target comprising a first circular bull's-eye surrounded by a series of concentric circles defining areas of radially outwardly diminishing score values, there being a second bull's-eye on said target larger than said first bull's-eye and symmetrical about the vertical diameter of said first bull's-eye, said second bull's-eye having a maximum transverse dimension equal to that subtended by said blade when viewed through said peep hole at a predetermined range, said bull's-eyes having one point only of the lowermost portions of their outer boundaries in common.

4. In a target, a first circular bull's-eye having a plurality of rings concentric of said first bull's-eye defining areas of progressively decreasing score values radially outwardly, a second circular bull's-eye superposed on and of larger diameter than, said first bull's-eye, said bull's-eyes being tangent at their lowermost peripheral portions and said second bull's-eye and one of said rings being tangent at their uppermost peripheral portions.

5. A target according to claim 3, said second bull's-eye being in the form of the upper half of a circle of larger diameter than said first bull's-eye, the horizontal diameter of which is tangent to said first bull's-eye at the lower portions of its circumference.

6. A target according to claim 3, said second bull's-eye being in the form of a square, the lower horizontal edge of said square being tangent to said first bull's-eye at the lower portion of its circumference.

FRED W. SCHAFFNER.
